US00D975012S

(12) **United States Design Patent** (10) Patent No.: **US D975,012 S**
Chen et al. (45) Date of Patent: **** Jan. 10, 2023**

(54) **MAGNETIC WIRELESS CHARGER FOR CAR**

(71) Applicants: **Wen Chen**, Guangzhou (CN); **Feng Yu**, Guangzhou (CN)

(72) Inventors: **Wen Chen**, Guangzhou (CN); **Feng Yu**, Guangzhou (CN)

(**) Term: **15 Years**

(21) Appl. No.: **29/786,420**

(22) Filed: **Jun. 1, 2021**

(30) **Foreign Application Priority Data**

Dec. 3, 2020 (CN) 202030742914.1

(51) LOC (14) Cl. **13-02**

(57) **CLAIM**

The ornamental design for a magnetic wireless charger for car, as shown and described.

DESCRIPTION

FIG. 1 is a perspective view of a magnetic wireless charger for car showing my present design;

FIG. 2 is a front view thereof;

FIG. 3 is a rear view thereof;

FIG. 4 is a left side view thereof;

FIG. 5 a right side view thereof;

FIG. 6 is a top view thereof; and,

FIG. 7 is a bottom view thereof.

1 Claim, 7 Drawing Sheets
